WILLIAM J. HAMMER, OF BOSTON, MASSACHUSETTS, ASSIGNOR TO HIMSELF,
AND FRANCIS R. UPTON, OF ORANGE, NEW JERSEY.

ELECTRICAL SWITCH.

SPECIFICATION forming part of Letters Patent No. 363,334, dated May 17, 1887.

Application filed December 30, 1886. Serial No. 222,956. (No model.)

To all whom it may concern:

Be it known that I, WILLIAM J. HAMMER, of Boston, in the county of Suffolk and State of Massachusetts, have invented a certain new and useful Improvement in Electrical Switches, of which the following is a specification.

The object of my invention is to produce a simple and efficient form of switch which shall be especially adapted for making and breaking very heavy currents, in that it makes and breaks contact at a large number of points simultaneously and quickly.

My invention consists in the novel devices and combinations of devices employed by me in accomplishing the above-named object, as hereinafter set forth and claimed.

In the accompanying drawings, Figure 1 is a top view of a switch embodying my invention, the operating-handle being shown in dotted lines; Fig. 2, a view of the same switch, partly in section and partly in elevation; Fig. 3, a top view, and Fig. 4 a section, of another form of circuit making and breaking wheel which may be used.

Referring first to Figs. 1 and 2, A is a suitable base, of wood or other insulating material. B is a ring or annular plate, of suitable metal, set upon the base A, and said base has an upwardly-extending collar, C, encircled by the plate B. A shaft or spindle, D, turns through the base and through a metal sleeve, E, secured beneath the base, from which sleeve extends a clamp, F, or other suitable device for connecting an electrical conductor, 2. The lower side of the base is preferably recessed at A' to accommodate these parts. The other conductor-terminal, where conductor 1 is joined to the switch, is a clamp or other connecting device, G, attached to plate B.

The spindle D carries a ratchet-wheel, H, which has upon its periphery notches I, whose surfaces are of metal, and notches K, whose surfaces are entirely of insulation. This ratchet is formed in the construction shown in Fig. 1 by the insertion of notched insulating-pieces a a, dovetailed into the wheel between the metal teeth.

Upon the plate B are pivoted a number of metal pawls, L, as many as there are notches

of either character on the ratchet. Each pawl has a spring, M, for forcing it into the notches.

The spindle D has a handle, D', for turning it. In the position of the switch shown in Fig. 1 the spring-pawls are all in the metal-surfaced notches, and the circuit is therefore closed from 1 to 2 through plate B, pawl L, ratchet H, and spindle D. To break the circuit the ratchet is turned, and the springs throw the pawls into the insulating-notches, 60 the breaking being thus performed by a quick spring action, and being accomplished at so many different multiple-arched points that, by reason partly of the quick action and partly of the division of the spark, the sparking effect 65 amounts to practically nothing. To close circuit again the ratchet is turned farther in the same direction, so that the pawls drop again into the metal-surfaced notches, this closing being also by the quick spring action, and the 70 spark being divided as before, so that again no spark occurs. The switch is thus especially adapted for circuits carrying heavy currents, such as those of electric-lighting and electric-railway systems.

Figs. 3 and 4 show another way of constructing the circuit-controlling ratchet-wheel. A metal wheel, N, is placed between two insulating-plates, O and O'. In Fig. 3 a portion of plate O is broken away to show the metal 80 plate. The plates may be secured together by rivets c c, or in other suitable manner, and the wheel thus formed is carried upon the spindle D, as before described.

The plates O and O' are of the same shape 85 and size, having teeth d and d', as shown. The metal plate N has teeth of such shape that between the teeth of the two insulating-plates the edges of the metal teeth project beyond the edges of the insulating-teeth. Thus a series of 90 notches alternately surfaced with insulation and with metal is formed, as in the other construction, and the operation is the same.

What I claim is—

1. In an electrical switch, the combination 95 of a wheel having alternate metal and insulating parts, said metal parts being connected with one circuit-terminal, and a series of contact-fingers bearing on said wheel, and all connected with the other terminal, whereby the 100

revolution of the wheel relative to said fingers makes or breaks the circuit at all said fingers at once, substantially as set forth.

2. In an electrical switch, the combination 5 of a ratchet-wheel having alternate conducting and insulating notches, said conducting notches being all connected with one circuit-terminal, and a series of spring-metal pawls, all connected with the other terminal and adapted 10 to enter said notches, whereby the revolution of the ratchet-wheel relative to said pawls makes or breaks the circuit at all said pawls at once, substantially as set forth.

3. In an electrical switch, the combination 15 of a notched metal wheel carried by a metal spindle, with which spindle one terminal of the circuit is connected, notched insulating parts attached to said wheel in such manner that metal and insulating notches alternate, 20 and a series of spring-metal pawls, all connected with the other circuit-terminal and adapted to enter said notches, substantially as set forth.

4. In an electrical switch, the combination 25 of the base of insulating material, the metal plate thereon, the spindle turning in said base and insulated from said plate, to which spindle a circuit-terminal is connected, the other terminal being connected to said plate, the 30 ratchet-wheel carried by said spindle, having

alternate metal and insulating notches, the surfaces of the metal notches being all connected with said spindle, and the series of spring-metal pawls, all mounted on said metal plate and adapted to enter said notches, substantially as set forth. 35

5. In an electrical switch, the ratchet-wheel consisting of superimposed toothed plates of metal and insulation, the teeth being so formed and arranged relatively to each other that 40 alternate metal and insulating notches are formed, in combination with the series of spring-metal pawls adapted to enter said notches, substantially as set forth.

6. In an electrical switch, the ratchet-wheel 45 composed of superimposed toothed plates of metal and insulation, the metal teeth projecting at their edges beyond the edges of alternate insulating-teeth, whereby alternate metal-surfaced and insulating-surfaced notches are 50 formed, in combination with the series of spring-metal pawls adapted to enter said notches, substantially as set forth.

This specification signed and witnessed this 28th day of December, 1886.

WM. J. HAMMER.

Witnesses:

J. B. WOODWORTH,
EDWARD E. PARKER.

It is hereby certified that in Letters Patent No. 363,334, granted May 17, 1887, upon the application of William J. Hammer, of Boston, Massachusetts, for an improvement in "Electrical Switches," errors appear in the printed specification requiring the following corrections, viz: On page 2, in lines 8, 20, 34, 43, and 52, the hyphens should be stricken out between the words "spring" and "metal;" and that the said Letters Patent should be read with these corrections therein that the same may conform to the record of the case in the Patent Office.

Signed, countersigned, and sealed this 24th day of May, A. D. 1887.

[SEAL.]

D. L. HAWKINS,

Acting Secretary of the Interior.
